UNITED STATES PATENT OFFICE.

SAMUEL M. CODE, OF CHICAGO, ILLINOIS.

SAFETY VEHICLE BODY.

Application filed November 22, 1926. Serial No. 150,110.

My invention relates to improvements in safety vehicle bodies, and it consists in the combinations, constructions, and arrangements herein described and claimed.

5 An object of my invention is to provide a vehicle body which is substantially puncture-proof, fireproof and water-tight.

A further object is to provide an improved 10 ventilating device, by means of which the interior of the body may be supplied with fresh air when the doors and portholes are closed during stormy weather.

A further object is to provide a vehicle 15 body having a ventilating device which is protected by means of a wave shield so that water cannot enter the body through the ventilator when waves are splashing against the sides of the body.

A further object is to provide a vehicle 20 body with a ventilator having automatic closing means, whereby the ventilator is automatically closed by means of gravity should the body capsize.

Other objects and advantages will appear 25 in the following specification, and the novel features of the invention will be particularly pointed out in the appended claims.

My invention is illustrated in the accompanying drawings, forming part of this application, in which.

Figure 1 is a longitudinal sectional view of my invention,

Figure 2 is a view substantially along the line 2—2 of Figure 1,

35 Figure 3 is an enlarged detail view showing the construction of the walls of the body.

Figure 4 is an enlarged detail view showing the means by which the wave shield is actuated.

40 Figure 5 is a detail view of the ventilator,

Figure 6 is a view along the line 6—6 of Figure 5,

45 Figure 7 is a detail view showing the means by which a portion of the ventilator is connected with the air-motor,

Figure 8 is a diagrammatic plan view of the body releasing mechanism, and

Figure 9 is a side elevation of the device shown in Figure 8.

50 In carrying out my invention I make use of an elongated body portion or shell A. As will be seen from Figure 3, I have provided outer and inner linings 1 and 2, respectively.

These linings are preferably of metal, or any suitable fireproof material. Adjacent the inner surface of the outer lining 1 is a relatively thick sheet of asbestos 3. Adjacent the outer surface of the inner lining 2 I have placed a thick layer of substantially punctureproof material 4, such as cork. Contiguous to the layer of cork 4 there is a second sheet of asbestos 5. The sheets of asbestos, 3 and 5, are spaced apart and held in spaced relation by means of a cellular structure 6. This cellular structure provides an air space 6' in the body portion, thereby increasing the resistance of the walls to sudden changes in temperature.

As will be seen from Figure 2, the bottom of the body is provided with a water keel 7. The inner surfaces 8 of the water keel 7 carry a balancing tank 9. This tank is preferably filled with any suitable liquid, thereby giving a necessary stability to the body A when it is floating upon water.

A floor comprising a series of slats 10 is provided. These slats are spaced apart so that any cargo carried in the body may be securely anchored to the floor. The slats are further spaced away from the bottom of the body and are held in spaced relation by means of springs 11. These springs give a desirable flexibility to the slats when they are carrying a load, thereby lessening the momentum of the cargo when the body tilts from side to side.

The top portion 12 of the body A is provided with a depressed portion 13. A ventilator 14 is disposed within the depressed portion 13. The side walls of the ventilator 15 are provided with a plurality of openings 15. A wave shield 16 is slidably supported by the side walls of the ventilator 14. The wave shield 16 has a laterally extending flange 17, which is provided with a downwardly extending edge 18. The flange 17 and the edge 18 tend to deflect any water which may happen to splash against the ventilator.

On two sides of the wave shield I have pivotally secured at 19 arms 20, which are provided with teeth 21. A pair of companion arms 22 is in operative engagement with the teeth 21, by means of a spring pressed pawl 23. The arms 22 are bifurcated below the point 23' for the purpose of retaining floats 24. These floats are preferably made

of cork and are spherical in contour. I have provided an outwardly extending curved flange 25 in connection with the bifurcated portion of the arm 22 whose purpose will be explained later.

The bottom of the ventilator 14 is open, as at 26, see Figure 6, and is provided with a supporting member 27, having a boss 28, a bevel gear 29, having an extended portion 30, and an integral fan 31 is rotatably supported by the boss 28.

A shaft 32, having a handle portion 33, is slidably disposed within the extended portion 30 of the bevel gear 29. The shaft is further supported by means of a guide 34. The upper end of the shaft 32 has an enlarged portion 35 which is retained by a boss 36 on the bottom side of a disk 37. The disk 37 is slidably disposed within the ventilator 14 and is drawn downwardly by means of springs 38.

The shaft 32 is provided with a trigger seat 39 which engages with a spring pressed trigger 40 when the disk 37 is in its raised position, as shown in Figure 1. This is the normal position of the disk, and, as will be observed, it is above the openings 15 in the walls of the ventilator 14.

An air-motor 41 is disposed on the top of the body portion A, as shown in Figure 1. Fans 42 are operatively secured to a shaft 43 having a bevel gear 44 secured to one end thereof. A flexible shaft 45 is in engagement with the air-motor by means of a bevel gear 46, which is in mesh with the gear 44. The upper end of the shaft 45 is supported by means of a bearing 47. The opposite end of the flexible shaft 45 is supported by means of a bearing 48, and is provided with a bevel gear 49 which is in mesh with the bevel gear 29. Thus it will be seen that the air-motor 41 is operatively connected with the fan 31 within the ventilator 14.

A sphere 50 is secured to the interior of the body A by means of suitable supporting straps 51. The sphere is hollow and is filled to about one half full with any suitable liquid 52. A float 53, preferably of cork, is disposed within the sphere and floats upon the liquid 52. Four cables 54 are secured to the float 53 in any suitable manner. These cables are run downwardly and around pulleys 55, thence toward the center of the sphere, as shown in Figure 5. The cables 54 are run through individual openings in a guiding member 56 and are then tied into one strand 57. This strand is wound around a pulley 57' and around a portion of the pulley 55, thence out through an opening 58 in the sphere. The strand 57 is next wound around a pulley 59 secured to the ventilator 14. The strand 57 is then run through a pulley 60 and connected to the spring pressed trigger 40. Thus it will be seen that, when the body A tilts, this causes

the liquid within the sphere to change its level with respect to the float 53, thereby causing the float to move the cable 55.

The rear end of the body A is provided with a door 61.

Hoist loops 62 are secured to the top of the body A.

The front and rear ends of the body are provided with loops 63, which permit the body to be towed by any suitable means.

In Figure 9 I have shown a portion of the bottom of the body A provided with lugs 64. These lugs have holes 65 in registration with holes 66 in lugs 67 which are secured to any suitable chassis 68. Pins 69 are passed through the holes 65 and 66 respectively, thereby connecting the lugs 64 and 67. Cables 70 are secured to the forward end of the pins 69 and are secured to a cross bar 71. A lever 72 is secured to the cross arm 71 at 73. A fulcrum is provided at 74. It will thus be seen that when the upper end of the lever 72 is pulled backwardly, the cross arm 71 will be caused to move forwardly, thereby pulling the pins 69 out of engagement with the lugs 64 and 67. This will then release the body from the chassis 68.

The front end of the body A is provided with a window 75. Port holes 76 are disposed on each side of the body.

A safety hatch 77 is provided in the top of the body A.

From the foregoing description of the various parts of the device, the operation thereof may be readily understood. Let us assume that the body or shell A is mounted on the runners of an ice boat propelled by sails or other means and that the ice boat runs out into open water. The body A may then be disconnected from the runners by actuating the lever 74 which will pull out the pins 69, thereby releasing the body so that it can float in safety upon the water.

Should the weather be bad so that the port holes and entrance doors must be closed, the air-motor 41 is permitted to operate, thereby actuating the flexible shaft 45, which in turn causes the suction fan 31 to rotate. The rotation of the fan 31 will then draw air in through the opening 15 in the ventilator 14 so that the interior of the body may at all times be supplied with fresh air.

As will be observed from Figure 2, the floats 24 which are disposed on each side of the body A are arranged to actuate the wave shield 16. When the waves splash against the sides of the body, the arms 22 and 20 on either side of the body are moved upwardly by means of the float 24 and the curved flange 25, thereby moving the wave shield 16 upwardly so that it covers the openings 15, thus preventing water from entering the ventilator. As the water recedes, the shield drops down to its normal posi-

tion and the float is permitted to drop down by means of the spring pressed pawl 23.

The disk 35 is normally above the openings 15 in the ventilator, and is held in this position by means of the spring pressed trigger 40 which is in engagement with the shaft 32 by means of the trigger seat 39. Should the body A be endangered by virtue of tilting over on its side or by capsizing, the liquid 54 will cause the float 53 to move the cable 57, which in turn will pull the trigger 40 out of engagement with the shaft 32. The disk 37 will now be drawn below the openings 15 in the ventilator by means of the tension in the springs 38. When the disk is underneath the openings 15, the body is completely closed so that no water can enter into the interior.

As will be observed, the body is lined with fireproof material, as shown in Figure 3. The sheets 1 and 2 are preferably metal, or any other fireproof material, and are further protected by means of the asbestos lining 3 and 5 respectively. The cork 4 is substantially puncture proof, which increases the safety of my body. The cellular structure is also fireproof and at the same time provides an air space 6', thereby giving the body a greater resistance to sudden changes in temperature.

I claim:

1. A safety vehicle body, comprising a shell, a ventilator carried by the shell and having a plurality of openings for permitting air to pass therethrough, a wave shield yieldingly carried by said ventilator, and means for reciprocating said wave shield, thereby permitting said wave shield to close and open said openings.

2. A safety vehicle body, comprising a shell, a ventilator carried by the shell and having a plurality of openings for permitting air to pass therethrough, a wave shield carried by said ventilator and arranged to close and open said openings, a suction fan disposed within said ventilator, an air-motor carried by said body, and flexible means operatively connecting said suction fan and said air-motor.

3. A safety vehicle body, comprising a shell, a ventilator having a plurality of openings, a wave shield carried by said ventilator and arranged to close and open said openings, a suction fan disposed within said ventilator, an air-motor carried by said body and arranged to actuate said suction fan, a disk slidably disposed within said ventilator, said disk being normally supported above the openings in the ventilator, and automati-

ic means for releasing said disk, thereby permitting the disk to be drawn downwardly to a position below the openings in said ventilator.

4. A safety vehicle body, comprising a shell, a ventilator having a plurality of openings, a wave shield operatively carried by said ventilator, said wave shield being provided with a laterally extending flange, and having a pair of actuating floats for raising and lowering said wave shield.

5. A safety vehicle body, comprising a shell having an outer and an inner lining, said outer and inner linings being watertight and fireproof, a punctureproof layer adjacent one surface of said inner lining, a pair of fireproof sheets disposed between said punctureproof layer and said outer lining, and cellular means for holding said fireproof sheets in spaced relation, whereby an air space is formed between said fireproof sheets.

6. A safety vehicle body, comprising a shell, a ventilator having a plurality of openings, a disk slidably disposed within said ventilator, means for normally supporting said disk in a position above said openings, an automatic releasing device carried by said body, and flexible means operatively connecting said automatic releasing device and said disk, whereby said disk may be released to fall to a position below said openings when said body and said automatic releasing device are tilted.

7. The combination with a safety vehicle body, of a ventilator having a plurality of openings, a disk slidably disposed within said ventilator and having a shaft arranged for manual actuation, a releasing device carried by said body, said releasing device containing liquid and having a float disposed upon said liquid, flexible means connecting said float and said shaft, whereby said shaft and said disk are released when said releasing device is tilted by virtue of the tilting of said body.

8. The combination with a chassis, having a plurality of lugs provided with openings, of an elongated body portion having a bottom, a keel carried by said bottom, a flexible floor disposed within said body portion, said body portion being provided with a plurality of lugs having openings in registration with said first named openings, a plurality of pins for operatively engaging said openings, and means for disengaging said pins, thereby freeing said body from said chassis.
